(57) **CLAIM**

The ornamental design for a shell, as shown and described.

DESCRIPTION

FIG. 1 is a top isometric view of a shell;
FIG. 2 is a bottom isometric view of the shell;
FIG. 3 is a cross-sectional side view of the shell taken from
line 3-3 in FIG. 5;
FIG. 4 is an enlarged detailed view of the shell taken from
line 4 in FIG. 3;

(Continued)

FIG. 5 is a top plan view of the shell; and,
FIG. 6 is a bottom plan view of the shell.

1 Claim, 4 Drawing Sheets
